UNITED STATES PATENT OFFICE.

WILLIAM WRIGHT, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR END.

Application filed January 22, 1924. Serial No. 687,854.

This invention relates in general to improvements in railway freight cars and more particularly to improvements in the construction of the end walls of such cars. It has for its principal objects a construction of the end framing of the car which will efficiently resist outward stresses and inward bending when pressure is applied to the end wall as the result of shifting of the cargo in the car and any weaving motion the car may be subjected to; the provision of end wall panels formed to provide attaching surfaces which project transversely with respect to the general plane of said panels so as to provide a deeper resisting body; the provision of a panel so formed that the attaching surfaces or flanges will not bend out of their normal position; the provision of an end wall having flanges for attachment to the side of the car which are arranged in a plane substantially longitudinally of the car thereby providing a strengthened and rigidified attachment at the framing of the car; and such other objects and advantages of the invention as may be found to obtain in the structure hereinafter set forth and claimed.

In the accompanying drawings, forming a part of this specification, and showing a preferred form and manner in which the invention may be embodied and practiced, but without limiting the claimed invention specifically to such illustrative instance or instances:

Figure 1 is an end elevational view of a railway car embodying the invention.

Fig. 2 is enlarged detailed and elevational view of part of one end of a railway car embodying the invention.

Fig. 3 is a side elevational view of the end portion of the side of a car showing a manner of securing the corner post to the side sills.

Fig. 4 is a horizontal cross sectional view taken on the lines 4-4 of Fig. 1.

Fig. 5 is an enlarged detailed horizontal cross sectional view of one corner of the car as shown in Fig. 4.

Fig. 6 is a vertical cross sectional view taken on the line 6-6 of Fig. 2.

Fig. 7 is a horizontal cross-sectional view taken on the line 7-7 of Fig. 2.

Referring to the drawings, the framing of the car forming the supporting framework

for the end wall consists of metallic angle-bar side plates 11, side sills 12, extending longitudinally of the car, and the end angle 13, extending across the car from side sill to side sill and rigidly secured thereto. At the upper part of the car is a relatively heavy pressed steel member 14 of U-shaped cross section which extends across the car from side plate to side plate and is provided at its ends with transversely bent portions 15 not only affording rigid fastening means for the side plates but also serving to strengthen the member 14 against buckling. The member 14 is pressed outwardly at each end at 15' to fit against the web of the adjacent corner post of the car to which the portion 15' is riveted. This member 14 may be considered the end plate of the car and consists of a vertical web 16 having a transversely and inwardly extending bottom flange and a similar upper flange 17 but of relatively greater length.

If desired a metallic floor for the car may be used and in the present instance this floor is arranged below the end sill angle above mentioned and extends a short distance 19 out beyond said end sill angle. 20 indicates the usual wooden flooring and 21 the usual wooden sheathing that is secured to the wooden securing or nailing strips 22.

The corner posts 23 are shown as of channeled form having a web 24 extending transversely of the car, an inside flange 25 and an outer flange 26. A wooden strip 27 for nailing purposes is arranged in the channel of each post and the side sheathing 28 may also project into said channel, if desired.

End panels 29 are utilized to form the end wall of the car. Each of these panels consists of a vertically extending web 30 disposed between flanges 31 that project transversely with respect to said web and are connected to the latter through portions 32 substantially parallel with said web but spaced therefrom by portions 33 which are inclined transversely to the plane of said web 30, all of said portions and flanges being formed integrally with said web and being pressed out of a flat sheet of metal. It will be noted that the web 30 is arranged in a plane between the inner edge 34 of the flanges 31 and the portion 32. To further strengthen and rigidify said panels and to further rigidify said flanges 31 against bending out of their

- normal positions, the flanges 31 and portions 32 and 33 are deformed in spots 35 by pressing said flanges 31 and portions 32 and 33 inwardly thereby providing abutments between said flanges 31 and said webs 30. The inner edges of the flanges 31 of each alternate panel are further flanged at 36 to engage against the inner edge of a next adjacent panel, thereby providing a smooth or finished surface against the wooden sheathing. The adjacent flanges 31 of adjacent panels 29 are abutted against each other as shown in Fig. 4 and are riveted together as at 37 thereby rigidifying said panels and providing a weather-tight joint. The side flanges 31 adjacent the corner posts are riveted to said corner post flange 25 in a line substantially parallel with the direction of the stresses and thrusts that the ends are subjected to, which provides a stronger fastening than a flat fastening at these points of attachments, that is, a stronger fastening than would obtain were the panels secured to the web of the corner posts. At their upper ends the webs of the panels are riveted to the web of the member 14 by rivets 38 and the portions 32 are riveted at 39 to an end cover plate 40 that extends down below the top edges of the panels and thereby weather-proofs the upper ends of said panels. This cover plate 40 extends up to the roof 41 and is flanged inwardly at 42. Secured to the inside of said cover plate 40 is an angle piece 43 having a flange 44 riveted to the cover plate and an inwardly extending piece 45 fitting over the tops of said panels and riveted at 46 to the top flange of said pressed steel member 14 which rigidly holds said cover plate against buckling. The upper and lower ends of said flanges 31 are cut away as at 47 so that said member 14 at the top and the end sill angle at the bottom may extend across the car and engage the webs 30 of said panels.
- At their lower edges, said panel webs 30 are riveted at 48 to the end sill angle and as the floor of the car is carried out beyond said end sill angle a weather-tight joint is obtained at the floor of the car. 49 indicates the usual push pole pockets riveted at 51 to the webs 30 and the end sill angle and riveted at 52 to the outer flange of the corner posts. 53 is the usual tie brace that ties the corner posts to the side sills.
- At the center of the end just back of the coupler 54 is provided an angle piece 55 riveted to the floor and to the panels to strengthen the panels where they are subjected to buffing and pulling strains.
- From the foregoing description it will be apparent that the end construction is so arranged, rigidified and strengthened that all parts subjected to the greatest strains are given a beam effect and the danger of the side plates or end plates collapsing or bend-

ing is avoided by the cooperative arrangement of the parts which so act together as to strengthen each other under diversified strains.

The invention as hereinabove set forth is embodied in a particular form of construction but may be variously embodied within the scope of the claims hereinafter made.

I claim:

1. In combination with corner posts, end plate and end sill: a plurality of vertically extending paneled girder plates rigidly secured at their upper ends to the end plate and at their lower ends to said end sill, the girder plates adjacent to the corner posts each having a flange extending transversely to its body, and said flanges being disposed between and rigidly secured to said corner posts.

2. In combination with the side sills and side plates, the end plate, end sill angle and corner posts forming a rigidified end frame of the car, vertical panel beams secured at their upper ends to said end plate and at their lower ends to said end sill angle, each panel having side flanges connected with the body of the panels by a portion arranged parallel with said body and a portion arranged obliquely to said body, portions of said oblique and parallel portions being pressed in to maintain said flanges from bending, the main body of said panels being in a plane between the inner and outer edges of said flanges, the flanges of adjacent panels being secured together to form a weather-tight joint, and the flanges adjacent to the corner posts being rigidly secured thereto.

3. In combination with the end plate, end sill, corner posts, side plates and side sills: vertical panel beams rigidly secured at their upper ends to the end plate and at their lower ends to the end sill, each side of said panels being bent outwardly and obliquely and then bent substantially parallel with the body of the panel, said parallel portion terminating in an inwardly directed flange right-angularly disposed with respect to said panel body and the inner edge of said flange terminating back of said panel body.

4. In combination with the end plate, end sill, corner posts, side plates and side sills: vertical panel beams rigidly secured at their upper ends to the end plate and at their lower ends to the end sill, each side of said panels being bent outwardly and obliquely and then bent substantially parallel with the body of the panel, said parallel portion terminating in an inwardly directed flange right-angularly disposed with respect to said panel body and the inner edge of said flange terminating back of said panel body; portions of said oblique and parallel portions and said flange being inwardly pressed to rigidify said flange.

5. In combination with the framing of the

end of a railway car: a plurality of paneled beams forming the end wall of the car, said panels comprising a main body and edge flanges, the said edge flanges having transversely extending depressions for rigidifying said flanges.

6. In combination with the framing of the end of a railway car: a plurality of paneled beams forming the end wall of the car, said 10 panels comprising a web and outwardly extending obliquely arranged edge portions terminating in flanges substantially normal to said web the said flanges constituting faces adapted to be secured to similar flanges 15 of adjacent panels.

7. In combination with the framing of the ends of a railway car: a plurality of paneled beams forming the end wall of the car, said panels comprising a web and outwardly extending obliquely arranged edge portions 20 terminating in flanges extending transversely to said web, portions of said oblique portions and said flanges being deformed to rigidify said edges of the panel.

8. In combination with the framing of the end of a railway car: a plurality of paneled beams forming the end wall of the car, said panels comprising a web and outwardly extending obliquely arranged edge portions 30 terminating in a lateral portion, said lateral portion terminating in a flange disposed at an angle to said web and extending back of the main body of the panel.

9. In combination with the framing of the end of a railway car: a plurality of paneled beams forming the end wall of the car, said panels comprising a web and outwardly extending obliquely arranged edge portions 35 terminating in a lateral portion, said lateral portion terminating in a flange disposed at an angle to said web and extending back of the main body of the panel; said oblique and lateral portions and said flange being deformed in spots to rigidify said panels.

10. In combination, side plates, side sills, corner posts, end sill and end plate, said end plate having a web and upper and lower flanges, said end plate being secured at each end to said side plates, metallic panels extending vertically, said panels consisting of

a web and outwardly protruding sides, said sides consisting of a portion oblique and a portion parallel with respect to said web, said parallel portion terminating in a flange forming an angle with said web, the flanges of adjacent panels being rigidly secured together, and the flanges adjacent the corner posts being rigidly secured thereto, the portions of said flanges at their upper and lower ends being cut away, said end sill 55 angle having a vertical portion extending across the car and riveted to said panel webs and passing through the cut away portions of the flanges, the bottom of said end sill angle being secured on the floor 60 of the car which extends beyond the outer surfaces of said panels, the end plate passing through the cut away portions at the upper end of said flanges and the web of said 65 end plate being riveted to the webs of said panels, an end cover plate having a depending portion weather-proofing the outer top edges of said panels and an angle plate secured to said end plate and to said end cover 70 plate.

11. An end construction for railway cars comprising, in combination: side plates, an end plate having a web and top and bottom flanges, the ends of said end plate being riveted to said side plates, side sills, corner 80 posts and an end sill, vertically extending metallic panels having a web and side flanges, said web and side flanges being connected by a deformed portion, the upper and lower edge of said flanges being cut away to 85 receive the end plate and end sill respectively which extend across the car and are riveted to the webs of the panels, a metal end cover plate secured over the top of said panels, said 90 cover plate having a depending portion weather-proofing the upper edges of said panels, said end cover plate and end plate being secured together by an angle piece, wooden nailing strips secured vertically to the webs of said panels and horizontally extending match boards secured thereto.

In testimony whereof I have hereunto set my hand.

WILLIAM WRIGHT.
